Blotter

Attorney

UNITED STATES PATENT OFFICE.

JOHN H. COOK, OF SALT LAKE CITY, UTAH.

WINDOW SCAFFOLD.

Application filed April 11, 1923. Serial No. 631,450.

To all whom it may concern:

Be it known that I, JOHN H. COOK, a citizen of the United States, residing at Salt Lake City, in the county of Salt Lake and 5 State of Utah, have invented certain new and useful Improvements in Window Scaffolds, of which the following is a specification.

The present invention relates to means for supporting a person with safety outside a 10 window or other opening in a wall, and the object is to provide a structure of a novel and simple character that can be compactly folded, so that it will occupy but little space when not in use, and when extended and 15 placed in use, will constitute a practical and safe support. The device moreover is readily adjustable to different sized openings.

In the accompanying drawing:—

Figure 1 is a plan view of the preferred 20 embodiment of the invention.

Figure 2 is a view in elevation of the same.

Figure 3 is a detail view in side elevation of one of the holding brackets.

Figure 4 is a detail sectional view on the 25 line 4—4 of Figure 1.

In the embodiment disclosed a guard railing is employed, comprising a pair of sections 5 preferably in the form of an open framework and hingedly connected as shown 30 at 6, so that they may be swung to different angular relations or brought close together. The lower front corners of the sections 5 may have bearing knobs 5^a. One of these sections is provided at its lower edge with a 35 horizontal supporting bracket 7. The two sections are adapted to be held in angular relation by means of an extensible bar or rod, comprising telescoping sections 8 and 9, the section 8 being journaled, as shown at 10, 40 upon the bracket 7, and the section 9 having a terminal hook 11 adapted to engage in an eye 12 on the free end of the opposite rail section to that carrying the bracket 7. The telescoping rod sections 8 and 9 are held in 45 adjusted relation by a pin 13 passed therethrough, the section 9 having a plurality of openings similar to those in the hook member 19 illustrated in detail in Figure 4, and hereinafter described. A platform 14 is 50 journaled on the rod 8—9 by suitable straps 15, and is generally triangular in form, one of its margins being adapted to rest upon the bracket 7, the other opposite margin having a finger 16 that rests upon the lower bar 55 of the opposite guard rail section 5.

Journalized upon the front vertical bars of

the sections 5 as shown at 17^a are horizontally swinging bracket elements 17 having projecting socket extensions 18 at their lower ends which extensions are also journaled 60 on the front vertical bars of the sections 5, as shown at 18^a. In the sockets of said extensions are slidably mounted the shanks 19 of cushioned hooks 20 that are adapted to engage the inner sides of the window-frame. 65 The shanks 19 are provided with a plurality of openings 21 through which can be passed securing pins 22. Interposed between the extensions 18 is a spreader consisting of a tubular section 23 journaled, as shown at 24, 70 on one of the extensions 18, so that it may be swung in a vertical plane. The other extension has pivotally and slidably connected thereto, as shown at 25, a rod section 26 that can be swung in a horizontal plane. 75 The rod section is adapted to telescope into the tubular section and is held in different positions by a pin 27 adapted to engage in any of a series of openings in the rod or in other words, corresponds to the detail structure shown in Figure 4. If the parts 19 are swung outwardly or away from each other, the rod section 26 will disengage from the tubular section 23 and may be folded inwardly alongside the adjacent part 18 while 80 the tubular section can be swung upwardly parallel to the adjacent part 17, as a preliminary to folding the scaffold. 85

It will be evident that this structure when 90 not in use can be compactly folded, so that it will occupy but little space, and can be conveniently carried. On the other hand, it can be quickly set up and placed outside a window, so as to constitute a safe and convenient scaffold, the parts being readily adjustable in order that it may be made effective, irrespective of the size of the openings in which it is placed. 95

From the foregoing, it is thought that the 100 construction, operation and many advantages of the herein described invention will be apparent to those skilled in the art, without further description, and it will be understood that various changes in the size, shape, proportion and minor details of construction may be resorted to without departing from the spirit or sacrificing any of the advantages of the invention. 105

Having thus fully described my invention, what I claim as new, and desire to 110 secure by Letters Patent, is:—

1. A window scaffold comprising a guard

5 rail composed of sections pivoted together on an upright axis, devices carried by the free portions of the guard rail sections for supporting engagement with the walls of an opening, means for holding the sections and devices spaced apart to maintain such supporting engagement, and a platform that is supported between and by the rail sections.

10 2. A window scaffold comprising a guard rail composed of sections pivoted together on an upright axis, devices carried by the free portions of the guard rail sections for supporting engagement with the walls of an opening, an extensible spreader between the free ends of the guard rail sections, a platform that rests upon the spreader and the lower portions of the rail sections, and wall-engaging hooks pivotally mounted on the free portions of the rail sections.

15 3. A window scaffold comprising a guard rail consisting of a pair of sections hinged together at their adjacent ends and adapted to be placed in angular relation, a substantially triangular platform that fits between the sections and has portions that rest thereupon, and means pivotally mounted on the free ends of the rail sections for mounting the scaffold at an opening in a wall.

20 4. A window scaffold comprising a guard rail consisting of a pair of sections hinged together at their adjacent ends and adapted to be placed in angular relation, a substantially triangular platform that fits between the sections and has portions that rest thereupon, certain of said portions passing through the railing.

25 5. A window scaffold comprising a guard rail composed of sections pivoted together on an upright axis, devices carried by the free portions of the guard rail sections for supporting engagement with the walls of an opening, an extensible spreader between

45 the free ends of the guard rail sections, a platform that rests upon the spreader and the lower portions of the rail sections, wall-engaging hooks pivotally mounted on the free portions of the rail sections, and an extensible spreader between the hooks.

50 6. A window scaffold comprising two relatively swinging guard rail sections hinged together at their upright meeting edges, means for spacing their free ends apart, and a substantially triangular platform removably supported and extending across the space between the lower portions 55 of the said guard rail sections.

60 7. A window scaffold comprising two relatively swingable guard rail sections hinged together at their upright meeting edges, an extensible spreader between the free ends of the guard rail sections, hooks pivoted on said free ends, and an extensible spreader connecting the hooks.

65 8. A window scaffold comprising hingedly connected railing sections, a holding device between the same, and a platform movably mounted on the holding device and adapted to be placed between the railing sections when said sections are disposed in angular relation.

70 9. A window scaffold comprising railing sections hinged together, a holding bar detachably connecting the free portions of the sections to maintain them in angular relation, and a platform journaled on the bar and adapted to swing to a position between the lower portions of the railing sections and rest thereupon.

75 In testimony whereof, I affix my signature in the presence of two witnesses.

JOHN H. COOK.

Witnesses:

DAN B. SHIELDS,
ARTELL FUNK.
